ISAAC S. ALBIN, OF MEMPHIS, TENNESSEE, ASSIGNOR OF ONE-HALF TO JOSEPH A. PRUSCHA, OF MEMPHIS, TENNESSEE.

COMBINED MOP AND SCRUBBER.

1,331,477.

Specification of Letters Patent. Patented Feb. 24, 1920.

Application filed June 20, 1919. Serial No. 305,488.

To all whom it may concern:

Be it known that I, ISAAC S. ALBIN, a citizen of the United States, residing at Memphis, in the county of Shelby and State of 5 Tennessee, have invented a new and useful Combined Mop and Scrubber, of which the following is a specification.

This invention has reference to combined mops and scrubbers, and its object is to 10 provide an implement capable of being used as a mop or as a scrubber for cleaning surfaces where both devices may be needed, without the necessity of employing separate implements for the purpose.

15 In accordance with the invention there is provided a handle of suitable length, the handle being hollow and arranged for the reception of a hose by means of which water may be directed through the handle. A head, 20 which may be formed of pipe, is furnished at the appropriate end of the handle, and this pipe is cut away on one side to receive a portion of another head which may be made fast to or removed from the first- 25 named head and is designed to carry the fabric portion of a mop with the threads, constituting the mop, in part seated in the cutaway portion of the first-named head. There is also provided a scrubbing brush 30 of suitable size with means for clamping it to the first-named head and the latter is arranged with perforations to direct small streams of water onto the scrubbing brush, such streams of water being utilizable in 35 connection with the mop alone in case the scrubbing brush is removed from the first-named head.

The invention will be best understood from a consideration of the following detailed description taken in connection with 40 the accompanying drawing forming part of this specification, with the understanding, however, that the invention is not confined to any strict conformity with the showing 45 of the drawing, but may be changed and modified so long as such changes and modifications mark no material departure from the salient features of the invention as expressed in the appended claims.

50 In the drawing:—

Figure 1 is a plan view of the head end of the combined mop and scrubber, but omitting the fabric portion of the mop in order to display parts of the structure which 55 would otherwise be hidden.

Fig. 2 is a section on the line 2—2 of Fig. 1.

Fig. 3 is a section on the line 3—3 of Fig. 1.

Referring to the drawing, there is shown 60 a head 1 which may be formed of pipe shaped into a generally rectangular structure including side bars 2, 3, and end bars 4, 5. Connected to the mid portion of the side bar 2 is a pipe extension 6 properly 65 shaped and proportioned to constitute a handle and this pipe may terminate in or include a valve 7 beyond which the pipe 6 may be continued in the form of a hose 8, whereby water may be directed through the 70 valve 7 and pipe 6 into the head 1, the hose 8 being of course connected to some suitable source of water under pressure.

Along the side 2 the head 1 is provided with perforations 9 which may slant toward 75 the other side of the head so as to direct small streams of water away from the side 2 and from the plane of the head 1. The side 3 has a cutaway portion 10 along the greater part of its length and facing the side 2. 80

There is also provided a scrubbing brush 11 having a bristle carrying block or board 12 as is customary. The board 12 is grooved, as shown at 13, to seat the end bars 4, 5 to some extent, and extending lengthwise of the 85 board about midway of its width are grooves 14 designed to each receive an extension 15 of a clip 16, the other end of the clip having notches 17 to underride the heads of screws 18 carried by the board 12. The extensions 90 15 are so related to the board that, when seated in the grooves 14, turn-buttons 19 carried by the board 12 may be moved into holding relation to the extensions 15, thereby clamping the clips 16 onto the end members 4 and thus firmly securing the scrubbing brush to the head 1. The structure is such; however, that the scrubbing brush may be readily detached when desired by turning the buttons 19 from engaging relation to the 100 extensions 15 and withdrawing the clips 16.

Midway of the side 2 of the head 1 there is provided an upstanding ear 20 for receiving a threaded stem 21 projecting from one side of a frame 22 having an end bar 23 105 arranged to seat in the cutaway portion or opening 10 of the side bar 3. The bar 23 is designed to engage a mop fabric 24 and hold it by its intermediate portion seated in the bar 3, the bar 23 forcing the fabric 110

into the interior of the bar 3 through the cutaway portion 10. The fabric is forced into the bar 3 with any desired degree of pressure by a wing nut 25 applied to the threaded stem 21 and bearing against the ear 20. The mop fabric 24 will then surround the bar 3 and is long enough to reach a surface upon which the bristles of the brush 11 rest.

10 The scrubbing brush may be used alone or in combination with the mop, or the mop may be used alone or in combination with the scrubbing brush. The mop and its holding frame 22 may be entirely removed, 15 or the mop fabric may be turned back onto the other parts and there tied while the brush alone is being used.

Water may be supplied through the handle 6 distributing oppositely from the connection of the handle to the side bar 2 and flowing out through the perforations 9 toward and against the brush when the latter is in place, or toward the mop when the brush is removed. The water will also flow 25 along the end bars 4 and 5 and to and through the opening or cutaway portion 10 of the side bar 3, it being assumed that the perforations 9 are relatively small so that all the water reaching the side bar 2 does 30 not escape through the perforations 9. There are conditions where a floor or other surface has dirt thereon so tenacious to the floor as to require the action of the brush 11. There are other conditions where the 35 dirt does not cling to the floor and hence may be readily acted upon by the mop fabric 24. Again, the conditions may be such as to permit the use of both the scrubber and the mop, the scrubbing loosening the 40 dirt and the mop gathering it.

What is claimed is:—

1. A combined mop and scrubber, comprising a hollow handle and a head carried by and communicating therewith and composed of hollow side and end bars, one of the side bars having perforations directed toward the other side bar and the second side bar being longitudinally cut away toward the perforated bar, a scrubbing brush 45 and means for fastening it to the end bars of the head, and a clamp frame carried by the head and adapted to enter the cutaway side bar to secure a mop fabric in said cutaway portion.

55 2. A mop, comprising a head with a handle, said head being composed of side and end bars and both the head and handle being formed of pipe, one of the side bars having perforations directed toward the 60 other side bar and the latter being cut away

on the side toward the first side bar, and means for securing a mop fabric in the cutaway portion.

3. A mop, comprising a head with a handle, said head being composed of side and end bars and both the head and handle being formed of pipe, one of the side bars having perforations directed toward the other side bar and the latter being cut away on the side toward the first side bar, said 70 head being also provided with a clamp frame for a mop fabric, said clamp frame being carried by the head and co-operating with the cut-away side bar to hold the mop in said cutaway portion.

75 4. A combined mop and scrubber, comprising a head formed of pipe and composed of side and end bars, a handle fast to the head midway of the length of one of the side bars and also composed of pipe, the side 80 bar connected to the handle being perforated on the side toward the other side bar and the second-named side bar being cut away lengthwise on the side toward the first-named side bar, a scrubbing brush having means for securing it to the end bars of the head, and a clamp frame for the mop carried by the head and co-operating with the second-named side bar to clamp a mop 85 fabric in the cutaway portion thereof.

90 5. In a combined mop and scrubber, a hollow handle, a head on the handle of substantially rectangular shape and comprising side and end bars of pipe, and a brush adapted for attachment to the head, 95 and removable clips carried by the brush with one end of each clip countersunk into the brush and the latter being provided with a turn-button for each clip, the head being constructed to direct water onto the 100 brush.

6. In a combined mop and scrubber, a substantially rectangular head with means for directing water thereinto, said head having one side bar cut away toward the other 105 side bar, a clamp frame carried by that side of the head remote from the cut-away side bar and adapted to engage in the latter, whereby to clamp a mop fabric against the cut-away side bar with the fabric entering 110 said side bar, and means for holding a brush to the head.

In testimony, that I claim the foregoing as my own, I have hereto affixed my signature.

ISAAC S. ALBIN.
